Primary Examiner—Antoine Duval Davis

(74) Attorney, Agent, or Firm—Merchant & Gould P.C.

(57) **CLAIM**

The ornamental design for solid full arch dental model base, as shown and described.

DESCRIPTION

FIG. 1 is a perspective view of the present invention.

FIG. 2 is a top plan view thereof.

FIG. 3 is a bottom plan view thereof.

FIG. 4 is a side view thereof.

FIG. 5 is a front elevation view thereof; and,

FIG. 6 is a rear elevation view thereof.
